Specification for Design.

Patented Dec. 9, 1913.

Application filed September 24, 1913. Serial No. 791,662. Term of patent 3½ years.

To all whom it may concern:

Be it known that I, JOHN H. HAWLEY, a citizen of the United States, residing at No. 100 West Seventy-ninth street, in the borough of Manhattan, city, county, and State of New York, have invented a new, original, and ornamental Design for Buttons, of which the following is a specification, reference being had to the accompanying drawing, forming part thereof.

Figures 1 and 2 are side elevations at

right angles to each other of a button embodying my invention. Fig. 3 is a top plan view. Fig. 4 is a central vertical section of Fig. 1.

I claim:

The ornamental design for a button, substantially as shown.

JOHN H. HAWLEY.
